(57) **CLAIM**

The ornamental design for a tank for a hand operated sprayer, as shown and described.

DESCRIPTION

FIG. 1 is a perspective view looking downwardly from the right side of a tank for a hand operated sprayer embodying our design;

FIG. 2 is a front elevational view thereof, the rear elevational view being identical;

FIG. 3 is a bottom view thereof;

FIG. 4 is a top view thereof;

FIG. 5 is a right side view thereof; and,

FIG. 6 is a left side view thereof.
